UNITED STATES PATENT OFFICE.

ROYAL N. RIBLET, OF SPOKANE, WASHINGTON.

ANKLE-SUPPORT FOR SKATES.

No. 805,667.

Specification of Letters Patent.

Patented Nov. 28, 1905.

Application filed March 14, 1905. Serial No. 250,073.

To all whom it may concern:

Be it known that I, ROYAL N. RIBLET, a citizen of the United States of America, residing at Spokane, in the county of Spokane and 5 State of Washington, have invented certain new and useful Improvements in Ankle-Supports for Skates; and I do declare the following to be a full, clear, and exact description of the invention, such as will enable others skilled 10 in the art to which it appertains to make and use the same, reference being had to the accompanying drawings, and to the figures of reference marked thereon, which form a part of this specification.

15 My invention relates to improvements in skates, and the objects of my improvements are, first, to provide a skate having an ankle-supporting standard or brace pivotally attached to the rear end of the heel of the skate; 20 second, to provide a vertical supporting-standard for the back of the leg, that is of triangular form and that terminates in a twisted portion at the apex of the triangle, from which a yoke projects at right angles to the triangular support and surrounds the rear and 25 sides of the leg loosely and a leg-strap which is pivotally connected to the ends of the yoke, which allow freedom of movement of the leg and foot at the ankle-joint; third, to provide 30 a leg-brace for skates that forms a support for the rear and sides of the heel and back of the leg and that fits the natural curvature of the heel and leg and that pivotally supports the leg from the rear and permits perfect 35 freedom of forward and backward movement of the leg and that prevents twisting of the skate on either one side or the other and that will not slide up or down on the leg as the 40 skate is turned to one side or the other by the leg and foot of the wearer. I attain these objects by the mechanism illustrated in the accompanying drawings, in which—

Figure 1 is a side elevation of my improved leg-support for skates. Fig. 2 is a rear view thereof, and Fig. 3 is a plan view.

Similar numerals of reference refer to similar parts throughout the several views.

Referring to the drawings, the numeral 1 designates the runner portion of the skate, 2 the sole-plate, and 3 the heel-plate. A shoe 4 is adapted to be secured permanently by screws. At the rear edge of the heel-plate 3 I form a pivotal or hinge eye 6. This hinge-eye may be formed integral with the heel-plate; but it is preferably formed on a plate 7, that is secured by rivets or screws 8 to the

heel-plate. The hinge-eye is preferably made of the full width of the heel-plate in order to make a strong hinge-joint for the brace 9. This brace 9 is made of spring-steel wire and 5 is triangular in form. At its base a straight bar portion 10 extends loosely through the eye 6 and forms a wide strong supporting base bar for the triangular support. From the base-bar 10 the opposite sides curve outward 65 and backward for a short distance and then inward to fit the curve of the ankle and then again slightly outward to conform to the increasing size of the leg. The brace also tapers evenly on both sides from the opposite 70 ends of its hinge-bar to its top, which may vary from about five to about eight inches in height, and near its top the opposite sides are twisted tightly together, and then they are bent at right angles and are curved outward 75 into a yoke or stirrup 11, which is adapted to straddle the leg loosely at its back and opposite sides. This yoke is curved outward at its rear end quite a little larger than the size of the leg, so that the leg will have plenty of 80 room to move forward and backward in it and also be twisted in it considerably without bearing against its sides; but its pivotal eye ends are curved inward to fit close to the leg and are drawn against it by the clamping-strap.

The twisting of the wires at the top of the triangular brace not only very materially stiffens the base, but allows the yoke to be made to fit any sized leg.

90 The ends of the yoke are bent into rings or eyes 12 and 13. To the eye 12 a strap 14, which is preferably in the form of a loop, and one end of a leather band 15 are pivotally connected by a rivet 16, and the free end 95 of the strap-loop is provided with a buckle 17. The opposite end of this leather band and one end of a strap 18 are pivotally connected by a rivet 19 to the yoke-eye 13. The opposite end of the strap 18 is adapted to fit the buckle 100 17. This band I call the "leg-band." It is preferably made wide enough to make a very firm and easy-clasping band and is long enough to nearly meet around the leg, and the buckle-strap is buckled over it and is used to clamp 105 it tightly around the leg.

110 The operation is as follows: In the act of skating the heel is supported at the back and side portions close to the back portions, as the transverse curve of the heel will extend back between the wires of the triangular vertical brace or supporting-standard, and the

2
leg is placed within the yoke and the band is strapped securely to it. The leg is then free to bend at the ankle either forward or backward or sidewise in either direction, as the triangular brace will pivotally yield on a direct forward or backward motion, and the leg-band will pivotally turn also when these movements of the leg are made, while the band and yoke and the support will resiliently yield 10 under side or twisting strains of the leg.

One of the essential properties of the triangular form and construction of my brace is that it will spring and resiliently yield to all the torsional strains it will be subjected to 15 while skating in addition to pivotally swinging in unison with the forward and backward movements of the skater.

Having described my invention, what I claim as new, and desire to secure by Letters 20 Patent, is—

In a leg-support a triangular-shaped support or brace curved to fit the contour of the heel and back of the leg, comprising a looped spring-wire, the loop of which forms the base of the triangle, and having the apex of said 25 triangle formed by twisting the ends of said looped wire together, and having the ends of said looped wire bent at right angles to the vertical portion of said triangular-shaped standard and curved in opposite directions to 30 form a yoke-shaped stirrup that is adapted to inclose the rear and sides of the leg, and a leg-clamping strap pivotally connected to the ends of said yoke-stirrup.

In testimony whereof I affix my signature in 35 presence of two witnesses.

ROYAL N. RIBLET.
